DESIGN FOR A COMBINED PAINT BRUSH
AND SCRAPER

Winfield S. Manchester, Newton Center, and Herbert Hathaway, Medford, Mass., assignors
to The Sherwin-Williams Company, Cleveland,
Ohio, a corporation of Ohio

Application April 22, 1939, Serial No. 84,498

Term of patent 3½ years

To all whom it may concern:

Be it known that we, Winfield S. Manchester, and Herbert Hathaway, citizens of the United States, residing, respectively, at Newton Center, in the county of Middlesex and State of Massachusetts, and Medford, county of Middlesex, and State of Massachusetts, have invented a new, original, and ornamental Design for a Combined Paint Brush and Scraper, of which the following is a specification, reference being had to the accompanying drawing, forming a part thereof.

Fig. 1 is a side elevational view of the combined paint brush and scraper showing our new design; and

Fig. 2 is an edge elevational view thereof.

We claim:

The ornamental design for a combined paint brush and scraper, substantially as shown.

WINFIELD S. MANCHESTER,
HERBERT HATHAWAY.
